ATTORNEY.

Patented June 26, 1928.

Des. 75,636

UNITED STATES PATENT OFFICE.

JAMES H. METCALF, OF LOS ANGELES, CALIFORNIA.

DESIGN FOR A GASOLINE-DISPENSING TANK.

Application filed June 16, 1926. Serial No. 18,063. Term of patent 3½ years.

To all whom it may concern:

Be it known that I, JAMES H. METCALF, a citizen of the United States, and resident of Los Angeles, county of Los Angeles, State of California, have invented a new, original, and ornamental Design for a Gasoline-Dispensing Tank, of which the following is a specification, reference being had to the accompanying drawing, forming part hereof.

Fig. 1 is a front perspective of a gasoline dispensing tank showing my new design.

Fig. 2 is a similar rear perspective.

I claim:

The ornamental design for a gasoline dispensing tank as shown.

JAMES H. METCALF.
